UNITED STATES PATENT OFFICE.

JOHN F. RICH, OF SUMMERTOWN, ASSIGNOR OF TWO-THIRDS TO LUTHER L. FRIERSON, OF MOUNT PLEASANT, TENNESSEE.

BARREL-HOOP.

SPECIFICATION forming part of Letters Patent No. 431,916, dated July 8, 1890.

Application filed April 2, 1890. Serial No. 346,315. (No model.)

To all whom it may concern:

Be it known that I, JOHN FRANKLIN RICH, a citizen of the United States, residing at Summertown, in the county of Lawrence and 5 State of Tennessee, have invented new and useful Improvements in Barrel-Hoops, of which the following is a specification.

This invention relates to that type of barrel-hoops having a ratchet-tooth connection 10 between the hoop ends, as described and shown in the Letters Patent No. 410,447, issued to me September 3, 1889.

The object of my present invention is to render the hoop more practicable and useful 15 and adapt it for accommodating itself to different places on a barrel or similar vessel wherein the diameter varies throughout by reason of the bulge or swell. This object I accomplish by constructing the inner sides of 20 the hoop ends with a greater number of teeth than the outer sides to afford a range of adjustment whereby the hook can be expanded or contracted or lengthened or shortened, as it were, to accommodate itself to different 25 places on the barrel.

The invention is exhibited by the accompanying drawing, in which the figure is a perspective view of the two end portions of the hoop.

30 In the drawing, the numerals 1 indicate the end portions of a wooden barrel-hoop constructed to overlap one upon the other and each having a lap-notch 2, so that the lapped hoop ends may be brought one over the other 35 and the extremities carried under the body portion. The outer surface of each hoop end is provided with two ratchet-like teeth 3, and the inner surface is provided with three or more similar but opposing ratchet-like teeth 4. The number of teeth 3 may vary and the 40 number of teeth 4 may be increased; but for the purposes of my present invention the number of teeth on the inner surface must

exceed the number of teeth on the outer surface of the hoop ends. By this means a 45 range of adjustment is provided whereby the hoop can be expanded or contracted to accommodate itself to different places on a barrel. As an example, I will refer to a flour-barrel, which usually has two hoops at an end 50 or head, and these hoops in consequence of the bulging or swelling of the barrel cannot be of the same diameter, but differ in this respect from five-eighths to three-quarters of an inch. By providing a number of inner 55 teeth 4 greater than the number of outer teeth 3, I am enabled to slip the hoop ends one upon the other to increase or diminish the diameter of the latter to fit at any place on the barrel. 60

The present invention makes it possible to use a single tooth 3 on the outside of each hoop end while two or three teeth 4 on the inner side thereof will effect the required range of adjustment. 65

To securely preserve the interlocking engagement of the ratchet-teeth, I propose driving nails or similar fastenings 5 through the hoop ends at the points 6 after hoop has been fitted to the barrel. 70

What I claim is—

A wooden ratchet-tooth barrel-hoop having the lap notches 2 and provided near each end with a series of ratchet-teeth extending entirely across the inner and outer surfaces, and 75 the number of teeth on the inside surface being in excess of the number of teeth on the outside surface, substantially as and for the purposes described.

In testimony whereof I have affixed my signature in presence of two witnesses. 80

JOHN F. RICH.
